UNITED STATES PATENT OFFICE

117,491

DESIGN FOR A DISPENSER FOR CIGARETTES OR CIGARS

Walter L. Buszkiewicz, Lemont, Ill.

Application April 25, 1939, Serial No. 84,553

Term of patent 14 years

To all whom it may concern:

Be it known that I, Walter L. Buszkiewicz, a citizen of the United States, residing at Lemont, in the county of Cook and State of Illinois, have invented a new, original, and ornamental Design for a Dispenser for Cigarettes or Cigars, of which the following is a specification, reference being had to the accompanying drawing, forming a part thereof.

Figure 1 is a perspective view of the dispenser for cigarettes or cigars showing my new design; and

I claim:

The ornamental design for a dispenser for cigarettes or cigars, substantially as shown.

WALTER L. BUSZKIEWICZ.
